UNITED STATES PATENT OFFICE.

LEVI HUSSEY AND EDWARD McCANN, OF NEW YORK, N. Y., ASSIGNORS OF ONE-THIRD TO THEODOSIA HATCH, OF SAME PLACE.

GREASE-SEPARATOR FOR STEAM-ENGINES.

SPECIFICATION forming part of Letters Patent No. 447,827, dated March 3, 1891.

Application filed March 31, 1890. Serial No. 345,966. (No model.)

To all whom it may concern:

Be it known that we, LEVI HUSSEY and EDWARD McCANN, of the city, county, and State of New York, citizens of the United States, 5 have invented certain new and useful Improvements in Grease-Separators for Steam-Engines, of which the following is a specification.

The invention relates to a grease-separator 10 for the exhaust-pipes of steam-engines for separating the grease from the exhaust-steam and collecting it for use again.

The object of the invention is to provide a durable device of this character which will 15 effect a thorough extraction of the grease from the steam.

In the accompanying drawings, Figure 1 represents a side elevation of our improved 20 grease-separator, showing the same connected with a pump for drawing off from time to time the grease separated from the steam by the separator. Fig. 2 is a top view of the separator, with the top plate removed, and Fig. 3 is a detail side view of one of the wire 25 screens which are employed for catching the grease. Fig. 4 is a vertical transverse section of said screen; and Fig. 5 is a side view of a separator, showing a modified construction of the collecting-chamber and discharge 30 device.

Similar letters of reference indicate corresponding parts.

In the drawings, A represents the exhaust-pipe of a steam-engine. In the exhaust-pipe 35 A is arranged a separator B, which is composed of a square or oblong casing B', that is closed by a top plate B². Below the separator is arranged a collecting-chamber C, in which the grease separated from the exhaust- 40 steam is collected. The side walls of the casing B' are provided with vertical grooves b for inserting a number of screens D of suitable wire-gauze, which screens serve to some extent as baffles for retarding the outward 45 flow of the exhaust-steam, said screens forming contact-surfaces against which the exhaust-steam impinges, so that the grease or oil carried along by the same is intercepted and deposited on the wire screens and con- 50 ducted along the same, together with the steam condensed by this operation, into the

collecting-chamber C. A baffle-disk E is arranged midway between the screens D in the separator-casing B', said baffle-disk being of smaller diameter than the screens and supported by lateral arms e e in a frame E', which is supported in guide-grooves b in the side walls of the casing in the same manner as the wire screens. The baffle-disk E serves for the purpose of deflecting the exhaust-steam and causing it to travel around the entire circumference of the same, so that it is distributed equally over the wire-screens and prevented from passing directly in a straight line through the same, whereby the middle part of the screens would wear out 55 too quickly, and whereby a more effective action of the screens is obtained.

In the collecting-chamber C is arranged a float f, to the upper part of which is pivoted 70 a lever f', that is fulcrumed to lugs at the outside of the collecting-chamber, said lever being provided with a balance-weight at the outer end. To the outer end of the fulcrumed lever f' is pivoted a connecting-rod g, the opposite end of which is applied to an arm g' of a valve G, which is located in the steam-supply pipe h, that conducts the steam to the steam-cylinder of a pump P below the grease-separator B. The pump P is connected 75 by a suction-pipe p with the collecting-chamber C, the pipe communicating with an opening in the side wall of the same, the opening being arranged at such a height that when a float arrives at a level therewith it 80 will open the valve G of the steam-supply pipe, while when it falls below the said opening it will close the steam-supply pipe. Consequently, when the level of the grease floating on the water of condensation in the collecting-chamber C rises to a level with the opening p' of the suction-pipe p the float f 85 simultaneously opens the steam-supply pipe and produces the working of the pump P, so as to draw off the grease until the level in 90 the collecting-chamber falls below said opening. By the lowering of the float the valve is closed and the working of the pump interrupted. In this manner the pump is intermittently operated for removing the grease 95 and water of condensation, both being pumped into a suitable storage-receptacle, from which 100

the grease is removed for being cleaned and used again.

In the modified construction shown in Fig. 5 no pump is employed for removing the grease, but the pressure of the exhaust-steam utilized for forcing the grease through a discharge-pipe *g* to a suitable storage-receptacle whenever the level of the grease arrives at the discharge-opening in the collecting-chamber, at which point the float and its lever will open the valve in the discharge-pipe, so as to permit the discharge of the collecting grease by the steam-pressure of the steam on the same.

15 The advantages of our improved grease-separator are that nearly all the grease carried along by the exhaust-steam is collected, owing to the contact of the steam with the large number of wire baffle-screens, which 20 act like a net for intercepting the steam and catching the grease carried along by the same, and, secondly, that the grease is collected in the chamber below the separator and removed automatically from the surface of the 25 water of condensation, so as to require no

special attendant. From time to time the screens have to be removed for cleaning the same, which is accomplished by removing the top plate of the casing. When the screens are worn out, new baffle-screens are inserted, 30 which can be accomplished at a comparatively small expense.

Having thus described our invention, we claim as new and desire to secure by Letters Patent—

35

In a grease-separator for the exhaust-pipe of a steam-engine, the combination of a casing, a number of screens disposed therein, and a baffle-disk of smaller diameter than the screens supported centrally of the casing 40 between said screens, substantially as described.

In testimony that we claim the foregoing as our invention we have signed our names in presence of two subscribing witnesses.

LEVI HUSSEY.
EDWARD McCANN.
